(57) **CLAIM**

The ornamental design for a vehicle front bumper, as shown and described.

DESCRIPTION

FIG. 1 is a right upper perspective view of a vehicle front bumper, showing my new design;

FIG. 2 is a right side elevational view thereof, the left side being a mirror image;

FIG. 3 is a front elevational view thereof;

FIG. 4 is a rear elevational view thereof;

FIG. 5 bottom plan view thereof; and,

FIG. 6 is a top plan view thereof.

The dash-dash even broken lines surround portions of the vehicle front bumper as well as show other portions that form no part of the claimed design.

1 Claim, 4 Drawing Sheets
